UNITED STATES PATENT OFFICE.

JOHN G. WILSON, OF ELLENDALE, DELAWARE.

SAFETY GAS COCK.

Application filed December 18, 1924. Serial No. 756,720.

This invention is an improvement in safety attachments for the ordinary type of gas cock and includes a pair of spring pressed latches embracing the opposite edges 5 of the handle and pivotally secured thereto.

An object of this invention is to provide a safety device for gas cocks and in the construction shown, I provide a transverse 10 passage in the valve having positioned there-in an expansion spring for pressing the latches outwardly into engagement with the inner walls of the recesses formed in the casing.

Further advantages may be described as 15 the description proceeds and reference is had to the accompanying drawing, wherein like reference characters indicate like or corresponding parts throughout the several 20 views.

Referring to the drawing,

Figure 1 is a perspective view of the present application of this invention to a conventional type gas cock,

Figure 2 is a longitudinal sectional view 25 of the present invention,

Figure 3 is a section taken on the line 3—3 of Figure 2, and

Figure 4 is a detailed perspective view 30 of the oppositely disposed latches, showing the expansion spring positioned therebetween.

The gas valve casing 10 may be connected to the usual fuel pipe 11 and is provided 35 with diametrically oppositely disposed vertical recesses or grooves 12 entirely in its bore forming seats for receiving the outwardly projecting lugs 13 on the inner ends of the latches 14.

The latches 14 have their outer ends 40 15 arcuated to conform to the shape of the handle 16 of the gas cock, and said ends are formed with keepers overlapping the opposite edges of the handle 16 by means of the inwardly projecting flanges 17 which are 45 provided with openings 18 for receiving the stud 19 for pivotally securing the latches to the handle 16. The handle 16 is provided with the vertical lateral recesses or grooves 50 20 to receive the inwardly curved portions of the latches 14, these grooves 20 adapted to be brought into register with the vertical lateral recesses or grooves 12 which lie entirely 55 within the bore of the casing.

The usual valve 21 is provided with a transverse passage 22 parallel to the gas out-

let and terminating in the recess 20. Positioned within this transverse passage is an expansion spring 23 extending beyond the ends of the same engaging and pressing the inner ends of latches 14 outwardly so that the lugs 13 will engage in the recesses 12 of the valve casing thereby locking the valve against accidental turning.

In the present disclosure, the valve and handle have been shown disposed above the pipe line, but it is to be understood that the valve and handle carrying the pivoted latches may be disposed below the pipe line when so desired. The present invention 60 provides a safety attachment for the usual gas cocks and includes a construction which will prevent accidental turning of the valve when it is closed. In order to turn the valve to open the same it becomes necessary 65 to press the ends of the latches inwardly toward the axis and against the tension of the expansion spring, thereby withdrawing the outwardly projecting lugs from the recesses in the valve casing. When the valve 70 is unlocked it can be turned like any other valve, but when the valve is locked, the pivoted latches are pressed into the recesses in the valve casing by the expansion spring 75 and thereby prevent accidental turning of 80 the valve.

Having thus described the invention it is to be understood that minor changes may be made without departing from the scope 85 of the appended claims.

I claim:

1. A gas cock comprising a turning plug and bored casing, said plug provided with a transverse gas channel and a transverse passage parallel thereto and opening at its ends 90 through the plug, the said plug having a flattened handle portion, an expansion spring in said transverse passage, latches having keepers embracing the edges of the valve handle and pivoted thereto and extended across the ends of the transverse passage and actuated by the expansion spring therein and having outwardly projecting lugs at said extended portions, and the casing ported to cooperate with the valve 95 channel and having vertical recesses entirely within its bore adapted to receive the latch lugs under the tension of the expansion spring.

2. A gas cock comprising a handled transversely pierced turning plug and bored casing, the bore of said casing having diametri-

cally oppositely longitudinal grooves, said longitudinal grooves being entirely within the said bore, said plug seated within said casing and provided with a transverse spring receiving chamber, an expansion spring within said chamber, diametrically opposite latch arms having inwardly projecting flanges or ears for engaging and embracing the sides of the valve handle, said plug having diametrically opposite vertical grooves in the sides thereof, the latch arms pivotally

connected to the valve handle, the latch arms disposed in the vertical side grooves of the said plug and outwardly turned lugs on the inner ends of the latch arms for engaging within the vertical grooves of the bore, the respective vertical grooves of the plug and bore adapted to be brought into register to permit the gas cock to be locked in shut off position. ¹⁵

JOHN G. WILSON.
